UNITED STATES PATENT OFFICE

2,239,061

AUTOMATIC STOKER GAS ELIMINATOR

Earl J. Sourber, Pottsville, Pa., assignor to Klein Stove Company, Philadelphia, Pa., a partnership consisting of Nathan Klein, Gustav Klein, Harry W. Klein, Julius Klein, and Meyer Klein

Application June 11, 1940, Serial No. 339,870

3 Claims. (Cl. 110—44)

My invention relates to an automatic stoker gas eliminator of the type disclosed in United States Patents Nos. 1,830,798, 1,974,475 and 2,140,761.

As will be seen from the patents referred to, gases often develop in the fire pot, in the hopper, or in the coal tube, which are not thoroughly consumed and which flow back into the room or other establishment thus causing inconvenience and possible injury. Also, as will be seen from the patents referred to, various devices have been used for eliminating such gases, and, while all the examples referred to are more or less operative, I found, by repeated experiment, that they are all defective in at least one serious and material feature in that the means for providing for the disposal of the gas, while initially operative, sooner or later got clogged up necessitating service and repair at relatively frequent intervals, all of which seriously detracts from the utility and practicability of these expedients. This is due primarily to two causes, namely, the objectionable gases are sucked off more or less directly from the coal tube of an automatic stoker by means of the blower which is adapted normally to blow air into the wind box thus imparting to the gases a velocity which permits them to carry off the final particles of dust or pulverized coal, and also due to the fact that these gases are also more or less humid so that the contents of these gases tend to settle and cake around the various orifices thus clogging them up and rendering the construction inoperative.

It is therefore the object of my invention to devise a construction which will operate permanently, or at least for very long periods of time, without the necessity of servicing, and I have accomplished this object after protracted study and experiment by counteracting the two objectionable features above set forth so as to draw the objectionable gases somewhat indirectly, or at low speed and pressure, and also I have provided means for imparting to these gases a constant turbulence and also a drying effect to prevent the deposit of their contents thus keeping the orifices open and insuring satisfactory results.

Other novel features of construction and advantage will be more clearly understood from the following specification and the accompanying drawing, in which—

Fig. 1 represents a fragmentary top plan view of an automatic stoker embodying my invention.

Fig. 2 represents on an enlarged scale a sec-

tion on line 2—2 of Fig. 1, certain parts being shown in the reverse position from the showing of Fig. 1.

Fig. 3 represents on an enlarged scale a section on line 3—3 of Fig. 1.

Fig. 4 represents a fragmentary, perspective view, certain of the exterior walls being broken away to show details of construction.

Fig. 5 represents on an enlarged scale a fragmentary view in perspective showing still further details of my invention, certain parts being omitted.

Referring to the drawing in which like reference characters indicate like parts, and more particularly to Fig. 1, 6 designates a conduit, usually termed a "wind box" which encloses another conduit 8, known as the "coal tube" which in turn houses a feed worm 10. One end of the wind box 6 is closed and the other end of the wind box leads to a retort or fire pot (not shown), and one end of the worm 10 leads to the bottom of the hopper (not shown) containing the pulverized coal, while the other end of the worm 10 leads into the bottom of the retort or fire pot for propelling the coal from the hopper to the fire pot. The hopper and the fire pot, being conventional, form no part of this invention and therefore are not shown nor described. 12 designates a housing in which is a conventional blower which is driven by the shaft 14 and gears or the like in the gear box 16. The blower, the gear box shaft and driving mechanism are also conventional and hence not shown. The blower delivers air through the elbow conduit 18 and the opening 20 into the wind box 6. 22 designates a damper having the operating handle 24 for controlling the opening of the air inlet conduit 26, which opening is covered by the screen 28. In order to draw gases accumulating with-

in the tube 8, and which, if not disposed of, would seep out through the coal hopper or elsewhere, the tube 8 is provided with an opening 30. Seated upon the tube 8 and completely covering the opening 30 is a saddlelike member 32 which is suitably carried by the upper wall of the wind box 6 as at 34. It will be noted that the saddlelike member 32 is hollow and that it establishes communication between the coal tube 8 and the fresh air inlet extension 26, or at a point between the damper 22 and the screen 28 as best seen in Fig. 2. The member 32 is provided with one or more openings 36 in a side wall 38 thereof, one or more openings 40 in the end wall 42, one opening 44 in the other end wall 46 and 55 the other side wall 48 is blank or provided with

no openings at all. In the absence of all of the openings 36, 40 or 44, the blower will serve to suck the damp gases from the coal tube and force them back into the wind box 6 and into the fire pot, but this will happen only when the parts are newly installed and clean as otherwise the damp gases, being sucked rather forcefully from the tube 8, tend to carry sediment and the damp sediment settles about the edges of the opening 30 in the tube 8 as well as the walls of the member 32 thus causing them to clog and rendering the device inoperative. The provision of the openings 36, 40 and 44, or some of them strategically located as disclosed, causes some of the air under pressure in the wind box 6 to enter the saddlelike member 32 from more than one direction thus causing a turbulence that prevents precipitation of sediment, and, also, by supplying air under pressure from the blower, any monoxide content in the gases is supplied with fresh air and hence neutralized, and the moisture in the gases is absorbed so that the solid contents of the gases are dried and hence are capable of being carried by the air of the blower and forced back into the wind box 6 and hence into the fire pot without being allowed to settle or cake and thus clog the various ports. In other words, the admission of air from the wind box 6 into the saddlelike member 32 above the opening 30 leading from the coal tube 8 serves simultaneously to neutralize harmful gases, to dilute such gases, to dry such gases and other solid contents, and at the same time to create sufficient turbulence to prevent the precipitation and caking of sediment. In actual practice I have found it advantageous to distribute the openings 36, 40 and 44 as shown, but, since the object of my invention is to introduce relatively dry air under pressure from the wind box into the saddlelike member 32 in order to neutralize and dry the gases, and since a further object is to cause turbulence in order to prevent settlement or precipitation of the sediment content of the gases it follows that my invention is not limited to the provision of two openings 36 in the side wall 38, or the provision of two openings 40 in the particular end wall 42, or one opening 44 in the particular end wall 46, and that it is within the scope of my invention to vary the number and location of the openings 36, 40 and 44 in any manner that will not interfere with the accomplishment of the purpose indicated, all as hereinabove explained and as defined in the appended claims.

Having thus described my invention, what I claim as new and desire to secure by Letters Patent is:

1. An automatic stoker comprising a wind box, a coal feed tube extending within said wind box, a blower for delivering air under pressure to said wind box and an air intake duct for said blower, and means for eliminating gases accumulating in said coal tube comprising, a conduit extending through said wind box and interconnecting said air intake duct and said coal tube whereby communication is established between the interior of said coal tube and said air intake duct, there being an opening in a wall of said conduit intermediate said air intake duct and said coal tube and leading to said wind box for admitting some of the air under pressure in said wind box into said conduit and said air intake duct.
2. An automatic stoker comprising a wind box, a coal feed tube extending within said wind box, a blower for delivering air under pressure to said wind box and an air intake duct for said blower, and means for eliminating gases accumulating in said coal tube comprising, a conduit extending through said wind box and interconnecting said air intake duct and said coal tube whereby communication is established between the interior of said coal tube and said air intake duct, there being openings in opposite walls of said conduit intermediate said air intake duct and said coal tube and leading to said wind box for admitting some of the air under pressure in said wind box into said conduit and said air intake duct.
3. An automatic stoker comprising a wind box, a coal feed tube extending within said wind box, a blower for delivering air under pressure to said wind box and an air intake duct for said blower, and means for eliminating gases accumulating in said coal tube comprising, a conduit extending through said wind box and interconnecting said air intake duct and said coal tube whereby communication is established between the interior of said coal tube and said air intake duct, there being a plurality of openings in the walls of said conduit intermediate said air intake duct and said coal tube for admitting some of the air under pressure in said wind box into said conduit and said air intake duct.

EARL J. SOURBER.
